(57) **CLAIM**

What is claimed is the ornamental design for a body panels for a construction machine, as shown and described.

DESCRIPTION

FIG. 1 is a right front perspective view of the body panels for a construction machine showing our new design. The broken line showing of a construction machine in all the figures are for environmental purposes only and form no part of the claimed design.

FIG. 2 is a left front perspective view thereof.

FIG. 3 is a right side elevation view thereof.

FIG. 4 is a left side elevation view thereof.

FIG. 5 is a front elevation view thereof; and,

FIG. 6 is a top plan view thereof.
